(**) Term: **14 Years**

CLAIM

(21) Appl. No.: **29/173,341**

The ornamental design for “front panel for a computer system enclosure”, substantially as shown and described.

(22) Filed: **Dec. 27, 2002**

DESCRIPTION

(51) **LOC (7) Cl. 14-02**
(52) **U.S. Cl. D14/444**
(58) **Field of Search** D14/441-446;
D13/162, 184, 199; 312/223.2; 361/690-696

(56) **References Cited**

FIG. 1 is a perspective view of a front panel for a computer system enclosure showing my new design;
FIG. 2 is a front elevational view thereof;
FIG. 3 is a first side elevational view thereof;
FIG. 4 is an opposite side elevational view thereof;
FIG. 5 is a top plan view thereof;
FIG. 6 is a rear elevational view thereof; and,
FIG. 7 is a bottom plan view thereof.

The broken lines are shown in the views for illustrative purposes only and form no part of the claimed design.
